UNITED STATES PATENT OFFICE.

JESSE E. MATTINSON AND ERNEST J. MOODY, OF SAN FRANCISCO, CALIFORNIA.

MUCKING MACHINE.

Application filed May 11, 1925. Serial No. 29,836.

Our invention relates to mucking machines, and more particularly to mucking workings. This material must be loaded into cars for removal from the mine and mucking machines or shovelling machines are employed for this purpose. The mucking machine is preferably advanced on tracks as the work proceeds and these tracks serve to carry the cars into which the material is loaded by the mucking machine. 60

An object of our invention is to provide a mucking machine that can be operated in a narrow tunnel. 65

Another object of our invention is to provide a mucking machine that can excavate material and load it into cars without 10 swinging the dipper.

A further object of our invention is to provide a mucking machine having a bucket from which the dug material discharges due solely to the elevation of the bucket.

15 A further object of the invention is to provide a mucking machine in which the dug material discharges from the bucket to a conveyor, when the bucket is elevated.

20 The invention possesses other advantageous features, some of which with the foregoing, will be set forth at length in the following description, where we shall outline in full that form of the mucking machine of our invention, which we have selected for 25 illustration in the drawings accompanying and forming part of the present specification. In said drawings we have shown one form of mucking machine embodying our invention, but it is to be understood that we 30 do not limit ourselves to such form, since the invention, as set forth in the claims, may be embodied in a plurality of forms.

In the drawings:

35 Figure 1 is a side elevation of a mucking machine embodying our invention arranged on a track to dump material into cars on the track, part of the machine and cars being broken away to reduce the size of the figure.

40 Fig. 2 is a plan of the machine shown in Fig. 1.

Fig. 3 is a plan, on a larger scale, of the rotatable platform of our mucking machine, a section of the head-frame being taken on the line 3-3 of Fig. 1.

45 Broadly speaking, the mucking machine of our invention preferably comprises a base provided with a conveyor and a dipper or bucket and its operating mechanism mounted on said base for universal movement and adapted to discharge material collected in said dipper, through the dipper handle or boom onto said conveyor.

50 In mining operations, for which our mucking machine is especially adapted, it is necessary to handle large quantities of loosened earth or similar material which has

55 In the operation, as heretofore practiced with existing mucking machines, the dipper of the machine is lowered and crowded into the bank of material ahead of it to charge it with material. When the dipper is full, it 60 is elevated sufficiently to clear the cars and is swung from the front of the shovel approximately through a semi-circle to the rear of the shovel and directly above a car. The bottom of the dipper is dropped and 65 the excavated material falls into the car. The bottom of the dipper is then closed and the dipper is again swung through a semi-circle to its former position in front of the shovel. It is then lowered and the cycle of 70 operations is repeated. It is apparent that a narrow tunnel will preclude the use of a mucking machine of this type since there is not sufficient room for the dipper to swing from its excavating position to its car-loading position. 75

80 The mucking machine of our invention is designed especially for operation in a narrow tunnel. To this end, we provide a machine adapted to be run into the end of a 85 tunnel, but which can excavate and load material without swinging the dipper in a semi-circle from the front to the rear of the machine. In our machine, material collected in the dipper runs, when the dipper is raised, by gravity down the dipper handle or boom which is formed like a chute, and is discharged onto a belt conveyor which runs rearwardly in the tunnel and carries the material from the dipper handle to the 90 cars. 95

95 The preferred form of our mucking machine, which is illustrated in the drawings, comprises a base or main frame 6 which is preferably provided with wheels 5 which 100 run on a track 11 laid in the tunnel and the machine may be propelled by a mine locomotive or may itself be equipped with propelling means.

105 At the rear end of the base 6, a framework 7 is erected to carry an endless belt conveyor. The conveyor is disposed on the

framework in substantially a horizontal position and extends beyond the rear of the base 6 sufficiently to over-hang a dump car 9 standing on the track 11, to the rear of the mucking machine. If conditions permit, the conveyor is preferably extended to overhang a number of dump cars to the rear of the mucking machine so that the cars may be filled successively by being drawn under the discharge end of the conveyor in turn. Suitable means, such as an electric motor 12 and proper intermediate mechanism 13 are provided for driving the belt 14. The loading end of the conveyor preferably lies substantially directly over the center of rotation of a rotatable platform 15 mounted on the base.

The rotatable platform is pivoted at its center on a pin 19 secured to the base and 20 is carried by a plurality of wheels or rollers 21 arranged in a circle on the under side of the platform and engaging a track formed by the side of the ring gear 22 secured to the base concentric with the 25 center of the platform. A reversible electric motor 23 mounted on the platform drives a pinion 24 which is journalled vertically in the platform and meshes with the ring gear. The platform is thus readily 30 rotatable in either direction relative to the base and at the same time is solidly supported to withstand heavy loads.

The mast or head frame 17 for supporting the dipper and dipper handle and their 25 operating mechanisms is mounted on the forward end of the platform. The mast is made up of a pair of parallel upright columns, such as the channel irons 25, 26, spaced apart transversely and substantially 30 braced to the platform. The mast carries means for manipulating the dipper in loading and unloading operations, these means including mechanism for raising the dipper, for crowding it into the material 40 being worked, and for varying the effective length of the dipper handle. Journalled in the mast is a transverse shaft 27 to which is secured a pinion 28 which engages a rack 47 secured to the under side of the chute 50 29, which forms the dipper handle, and by rotation of the shaft, the effective length of the dipper handle is varied.

Suitable means are provided for driving the shaft 27 in either direction to raise and 55 lower the dipper, and in the present instance a separate drive is provided for the transverse or crowder shaft 27. Each end of the crowder shaft carries a crank 32, 33, fixed on the shaft so that the two cranks 60 are spaced 90 degrees apart in the direction of rotation of the shaft. A similar shaft 34 is mounted on the platform parallel to the crowder shaft and is also provided with comparable cranks 36, 37. The cranks at 65 the corresponding ends of the shafts are

connected by the connecting rods 38 and 39. The shaft 34 on the platform is provided at its center with a gear 40 which is one of a train of gears connecting the shaft with a reversible electric motor 31, which is also 70 preferably mounted on the platform.

The dipper and dipper handle which in the ordinary steam shovel are roughly a scoop mounted on the end of a boom, in our mucking machine are a unitary structure 75 comprising a chute 29 having a bottom 42, two sides 43 and 44, and one closed end 45. As is shown most clearly in Fig. 1 the dipper and dipper handle have bottom wall 46 which lie in the same plane and form substantially a common bottom wall. A longitudinal rack 47 is centrally disposed thereon, and meshes with the pinion 28 on the crowder shaft 27, so that when the pinion is rotated, the dipper and dipper handle are 80 projected or retracted according to the direction of rotation of the pinion. The rack extends practically the entire length of the bottom wall to permit a large range of movement of the dipper. The dipper and dipper handle also have common side walls disposed approximately at right angles to the bottom wall and which are spaced apart the same amount throughout the length of the dipper and dipper handle. At the 85 digging or excavating end, the side walls are made higher to increase the capacity of the dipper. The bottom wall and side walls form a chute which is closed at the dipper end by an end wall 45 preferably disposed 90 obliquely to the bottom wall. Teeth 48 are provided on the end wall and may be mounted to project over the leading edge to facilitate excavating.

Means are provided for raising and lowering the unitary dipper and dipper handle. One side wall of the dipper is provided with a suitable pulley 49 in alignment with a pulley 51 journalled at the top of one of the channel irons 25 forming the mast. A cable 105 52 is provided, having one end anchored to the top of the channel iron and engaging the pulley on the dipper, passing over the pulley at the top of the mast, and a winding around and being anchored to a drum 53 mounted 110 on a shaft 54 journalled in supports on the platform. The drum shaft is connected through suitable speed reducing gears 56 to a reversible electric motor 57 supported by the platform. A similar cable 58 and set of 115 pulleys 59, 60 are provided on the other side of the dipper and operate in conjunction with a drum 62 mounted on the same shaft and rotated with the drum 53. Each side of the dipper is thus provided with substantially a block and tackle, the two being arranged to operate in unison.

It will be noted in the foregoing description that the crowder shaft, the raising and lowering mechanism, the rotatable plat- 120 125 130

form, and the belt conveyor are each actuated by a separate electric motor. Universal movement is provided as each of the three motors causes motion in a different dimension. All the motors except the conveyor motor are reversible and each is equipped with a separate controller. The three motors are preferably provided with controllers 53', 54', 55' of the street-car type, which may be grouped together for convenience of operation at the front of the platform so that the operator may watch the operation of the dipper. Motors operating on compressed air or by other means may of course be used in place of electric motors.

Our mucking machine can be used for a variety of purposes not connected with mining, such as digging trenches, but it is particularly adapted for use in mines, and its operation may best be understood from a description of its use in that connection.

The machine is run into the end of a tunnel and the electric motors connected to a source of electricity. A train of dump cars is positioned at the rear of the mucking machine preferably with the overhanging end of the conveyor above the farthest car. The proper controller is operated to cause the motor 23 to revolve the platform slightly to one side of the center of the machine. The motor 57 operating the cable drum 53 and 52 is then set in motion to pay out the cable and lower the dipper and dipper handle. The motor 31 is then energized and by its motion, turns the pinion on the crowder shaft to force the dipper and dipper handle to be projected or crowded into the bank of material to be excavated. It is to be understood that the motors 57 and 31 may be operated in conjunction to position the dipper and dipper handle as may be required. They are then controlled either separately or together to raise the dipper from the lowered position, shown by the dotted lines in Fig. 1, to the upper position indicated by the full lines in Fig. 1. As the dipper is raised, it is filled with material. The teeth on the leading edge of the end wall are of assistance in scraping material from the bank ahead of the machine and aid in filling the dipper. As the dipper is being raised, the pinion 27 is rotated to shorten the effective dipper handle and place the end of the handle remote from the dipper over the end of the conveyor and to permit the chute or handle to assume sufficient inclination in the small tunnel to cause the material to flow by gravity through the chute. When the dipper 18 is in raised position, the material it has gathered runs by gravity down the chute-like dipper handle 29 and is discharged onto the belt conveyor 8 which carries it along and loads it into the cars 9, 10. When one car 9 is full, the mucking machine may be

moved forward or the cars moved backward to bring the next empty car 10 into position beneath the end of the conveyor. The dipper is raised and lowered, crowded into the bank, and by means of the rotatable platform, swung from side to side until the desired excavation has been made. The end of the dipper handle being above the conveyor and directly over the center of rotation of the platform, when the dipper is in the discharging position shown in Fig. 1 material may discharge on the conveyor even though the platform and dipper have been swung to one side. The mucking machine may then be moved ahead to excavate more material.

It is seen that our mucking machine provides means for removing material and loading it onto cars without swinging the dipper through a semi-circle from the front to the rear of the machine and is thus well adapted for use in narrow tunnels, and that due to the shifting of the dipper handle with respect to its fulcrum, that the dipper handle may be moved to such inclination to effect the gravitational discharge of the material, without raising the dipper to an excessive height, thus permitting the machine to be used in low tunnels. The operation of the machine is much quicker than the operation of the swinging boom type of machine, so that the material may be handled with greater dispatch and consequently at a lesser cost.

We claim:

1. In a mucking machine, a dipper adapted to receive and discharge material, a dipper handle forming a chute into which said dipper discharges, and a conveyor immediately below said dipper handle for receiving material from said dipper handle, said dipper handle being mounted for universal movement with respect to said conveyor. 100

2. In a mucking machine, a dipper for containing material, a dipper handle forming a chute upon one end of which said dipper is mounted and thru which material discharged from said dipper may pass, and a conveyor immediately below the other end of said dipper handle for receiving the material which passes thru said dipper handle, 110 said other end of the dipper handle being capable of universal movement with respect to said conveyor. 115

3. In a mucking machine, a dipper, a chute-like operating handle secured to the dipper, means for moving the handle longitudinally, means for rotating said handle, means for swinging the handle in a vertical arc to incline it sufficiently to permit the gravitational discharge of material therethru and a conveyor arranged immediately below said dipper handle to receive the material from the handle. 120

4. In a mucking machine, a mobile base, a rotatable platform mounted on said base 130

and having a mast thereon, a belt conveyor mounted on said base above said platform, and a unitary dipper and dipper handle fulcrumed on said mast and adapted to be raised and lowered, said dipper handle forming a chute for transferring material from said dipper to said belt conveyor when said dipper and dipper handle are in raised position.

10 5. In a mucking machine, a mobile base, a rotatable platform mounted on said base and having an upright mast thereon, means for rotating said platform, a belt conveyor, mounted on said base and extending over said platform, means for operating said conveyor, a unitary dipper and dipper handle fulcrumed on said mast, means for shifting the dipper and dipper handle vertically and horizontally with respect to the base, said 15 dipper handle forming a chute for transferring material from said dipper to said belt conveyor when said dipper and dipper handle are in raised position.

6. In a mucking machine, a mobile base, 20 a rotatable platform mounted on said base and having an upright mast thereon, means for rotating said platform mounted thereon, a belt conveyor mounted on and extending beyond said base, means for operating said 25 conveyor mounted thereon, a rotatable pinion on a shaft transversely mounted on said mast, means for rotating said pinion mounted on said platform, a rack engaging said pinion and mounted on and reinforcing the

bottom wall of a unitary dipper and dipper 35 handle, said dipper handle forming a chute for transferring material from said dipper to said belt conveyor, a block and tackle engaging said dipper and the top of said mast, and means for operating said block and 40 tackle.

7. In a mucking machine, a rotatable platform mounted on a base, a belt conveyor mounted on said base and having one end disposed substantially directly above the center of rotation of said platform, a mast on said platform having a movable dipper handle thereon, said dipper handle being adapted in one position to discharge material from one end thereof, the discharge end of said 45 dipper handle in discharge position being disposed directly above the center of rotation of said platform and above said belt conveyor.

8. In a mucking machine, a mobile base, 50 a rotatable platform mounted on said base, an upright mast mounted eccentrically on said platform and stationary relative thereto, a conveyor mounted on and at one end overhanging said base and at the other end 55 extending over said platform, and a unitary dipper and dipper handle mounted on said mast and adapted to discharge onto said conveyor.

In testimony whereof, we have hereunto 60 set our hands.

JESSE E. MATTINSON.
ERNEST J. MOODY.
